United States Patent Office

Des. 195,826
Patented Aug. 6, 1963

195,826

DOOR HANDLE

George W. Melcher, Bally, Pa., assignor to Bally Case and Cooler, Inc., Bally, Pa.

Filed Dec. 14, 1962, Ser. No. 72,864

Term of patent 14 years

(Cl. D10—8)

FIG. 1

FIG. 2

I claim:

The ornamental design for a door handle, as shown.
